CLAIM

The ornamental design for a tree stand container, as shown and described.

DESCRIPTION

FIG. 1 is a perspective view of a tree stand container with a partially exploded view showing my new design; FIG. 2 is an elevational view of the design of FIG. 1; all elevational views being the same;

FIG. 3 is a top plan view of the design of FIG. 1; FIG. 4 is a bottom plan view of the design of FIG. 1; FIG. 5 is a bottom plan view of the removable lid of the design of FIG. 1;

FIG. 6 is a cross-sectional view of the design of FIG. 1; FIG. 7 is a perspective view of a tree stand showing another embodiment of the invention;

FIG. 8 is an elevational view of the design of FIG. 7; all elevational views being the same;

FIG. 9 is a top plan view of the design of FIG. 7; and, FIG. 10 is a bottom plan view of the design of FIG. 7.
